ELECTRODE PAD AND TAPE THEREFOR

Francis C. Moore, 7327 Galloway Drive 46250, and Leon R. Perkinson, 6305 Hillcrest Lane 46220, both of Indianapolis, Ind.

Filed July 27, 1972, Ser. No. 275,860

Term of patent 14 years

Int. Cl. D24—01

U.S. Cl. D83—1 C

FIG. 1 is a plan view of one surface of the electrode pad and tape therefor of the present invention;

FIG. 2 is a plan view as in FIG. 1 showing the opposed surface;

FIG. 3 is an elevational view taken along sight line 3—3 of FIG. 1, showing a longitudinal edge;

FIG. 4 is an elevational view taken along sight line 4—4 of FIG. 1, showing a transverse edge; and

FIG. 5 is an elevational view taken along sight line 5—5 of FIG. 1, showing the distal transverse edge.

We claim:

The ornamental design for an electrode pad and tape therefor, substantially as shown and described.
